TAPE MEASURE
Michel Quenot, Besancon, Doubs, France, assignor to
Etablissements Quenot and Company, Besancon, Doubs,
France
Filed Jan. 24, 1966, Ser. No. 522,701
3 Claims. (Cl. 242—84.8)

This application is in part a continuation of my previous application Ser. No. 370,194 filed May 26, 1964, and now abandoned.

The present invention is concerned with a spiral or scroll-shaped casing for winding a tape of metal or fabric adapted to measure lengths and comprising a bottom and a cover assembled together by a peripheral bead with a tangential exit and associated with a mechanism for winding and unwinding the tape and with means for tangentially guiding the tape between the inside and the outside of the casing.

Unexpectedly, in accordance with this invention, it has been found that giving to a tape measure casing a scroll-shaped or many-centered spiral configuration in combination with providing guide rollers at the forwardly extending projection of the casing ensures the tangential winding of the tape and leads to greater accuracy in withdrawing it without slip back.

According to a feature of the invention, designed for metal retractable tapes the guiding means are constituted by cooperating opposed channels extending approximately along a tangent with reference to the cylinder defined by the convolutions of said tape inside the casing.

According to a further feature of the invention, the opening in the reinforcement is constituted by a slot shaped so as to guide the tape accurately with a smooth frictional action.

According to a still further feature of the invention, the tangential opening in the casing allows securing two rollers revolvably carried to either side of the tangential exit and arranged in a manner such that, on the one hand, the space inside the casing provided for the winding of the tape, may be entirely free and that on the other hand, the tape may be wound tangentially with reference to the cylinder formed by its convolutions, the diameter of which cylinder varies between a minimum when the tape is unwound and a maximum when the tape is wound without said tape frictionally engaging the outer ridges of the casing.

The accompanying drawing illustrates by way of example preferred embodiments of the invention. In the drawings:

FIGURE 1 is a plan view of a cover for the system;
FIGURE 2 is a plan of the bottom member of the system;

FIGURE 3 is a cross-sectional view taken along line III—III of FIGURE 1; and

FIGURE 4 is the same taken along line IV—IV of FIGURE 2;

FIGURE 5 is a cross-sectional view of the completed assembly.

FIGURE 6 is a detail view of a variant.

Shown in FIGURES 1 and 2 the system comprises a casing 1 enclosing a tape 2 wound over a drum 3 controlled by a crank 24 in FIGURE 5. The casing 1 is constituted by a scroll-shaped peripheral bead 5 formed by the inturned edges of a bottom 3a and of a cover 6. Said bottom and cover are assembled by means of a center screw which is not illustrated and four side screws such as 20, 22 in FIGURE 5 fitting in threaded posts A, B, C and D moulded integrally with the device and which hold

2

the cover and the bottom assembled in contacting relationship with drum 3. The end 7 of each spiral or scroll-shaped casing extends approximately along a line tangent to the periphery of the bead and terminates along an oblique line to form an opening 8 (FIGURE 5) through which the tape may pass out of the casing. At this tangential exit are secured two rollers 9 and 10 revolving round axes parallel with the axis of the drum 3, so that the tape 2 may slide between said rollers without engaging them or else while engaging one of said rollers or the other; but in all cases the tape remains in a direction tangential to the cylinder of a variable diameter formed by the convolutions of the tape inside the casing with the aid of the screw post A which extends inward toward the center axis and aids in preventing the tape from touching the edges of the casing.

It will be noted from FIGURES 3 and 4 that the present device is assembled by fitting together halves 3a and 6 which may be molded of plastic, and inserting the screws at A, B, C and D as well as the center screw previously mentioned. This holds true for the larger models such as a 10 yard measure. In smaller ones, the side screws can be dispensed with. In such embodiments, it is easier to replace the guide rollers by tangential grooves 20 as shown in FIGURE 6 provided on members 3a and 6.

Many modifications may of course be brought to the embodiments disclosed without widening the scope of the invention, as defined in the accompanying claims.

30 What is claimed is:

1. A portable tape-measure comprising a substantially scroll-shaped casing having a pair of interfitting elements having side walls with oppositely facing in-turned edges defining a concave annular intermediate casing portion, 35 means holding said elements mounted, a measuring tape coiled within said casing and selectively extensible outwardly of said casing, said intermediate portion having an outer peripheral forward projection substantially in a plane tangential to said casing with an end surface approximately in a plane normal to the first mentioned plane giving said casing said substantially scroll-shape, said end projection having an outlet through which said tape is extensible longitudinally outwardly of said casing, together with guide means near said outlet for preventing said tape from touching the edges of said casing.

2. A tape-measure according to claim 1, in which said projection has a pair of guide rollers rotatably mounted in said outlet for guiding the travel of said tape along a path there-between when said tape tends to move away from said path.

3. A tape-measure according to claim 1, wherein said peripheral projection has channels near said outlet for guiding said tape therein to said outlet.
